B. W. Klein INVENTOR

BY *Sigmund Skory*
ATTORNEY

UNITED STATES PATENT OFFICE.

BENJAMIN W. KLEIN, OF NEW YORK, N. Y.

ABRADING MACHINE.

Application filed January 5, 1924. Serial No. 684,562.

To all whom it may concern:

Be it known that I, BENJAMIN W. KLEIN, a citizen of the United States, and resident of the city of New York, in the county of 5 New York and State of New York, have invented certain new and useful Improvements in Abrading Machines, of which the following is a specification.

The present invention relates to improvements in abrading machines, such as are 10 used in finishing the edges of shoe soles and heels.

In machines of this type the abrading wheels or cylinders are usually disposed 15 within housings, means being provided for collecting loose particles of the grinder or work thrown off during the abrading operation, the last-mentioned means usually consisting of a suction fan, delivering the loose 20 particles into a container. In practice it has been found that some of the particles thrown off during the abrading operation adhere to the bottom of the housing, and, notwithstanding the fact that the said bottom 25 is slanting, the suction fan does not remove the same, so that they are apt to leave the housing through the open end thereof, thereby endangering the health of the attendant and other persons in the room.

30 I have heretofore proposed to provide an attachment for abrading machines, which prevents adhesion of the loose particles of the grinder and work thrown off during the abrading operation to the housing, said 35 attachment comprising a scraping means, in the form of rotary fan blades, within said housing, said fan blades scraping the loose particles off the bottom of the housing, so that the fan is adapted to move or deliver the same into the container connected 40 to the housing, the said attachment being described in application for U. S. Letters Patent, Ser. No. 646,388, filed by me on June 19, 1923. In practice it has been found that, 45 inasmuch as these fan blades are made of metal and cannot be covered by protecting means, they are apt to injure the hands of the operator in handling the work.

The main object of the present invention 50 is to overcome this difficulty by providing a flexible means, which not only cleans the bottom of the housing but also the abrading wheel.

With these and other objects in view, 55 which will more fully appear as the nature

of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the 60 spirit or sacrificing any of the advantages of the invention.

One of the many possible embodiments of the invention is illustrated in the accompanying drawings, in which:—

Figure 1 is a front elevation of a portion of an abrading machine constructed in accordance with the present invention; Fig. 2 is a vertical section taken through one of the abrading wheels, its housing and the 70 attachment constructed in accordance with the present invention, on a larger scale; and Fig. 3 is a section taken on line 3—3 of Fig. 2.

Referring now to the drawings, the numeral 10 indicates one of the transverse frame members of an abrading machine, provided with a bearing 11, in the latter being rotatably mounted a longitudinally extending shaft 12. This shaft may be 80 driven in any suitable manner from any suitable source of power, for instance by the intermediary of a belt, not shown, running over a pulley 13 on the said shaft. To the shaft is attached a plurality of abrading wheels or cylinders 14, each of the same being disposed within a housing 15, the front of which is open, as clearly shown in Figs. 1 and 3 of the drawings. These housings are each provided with a slanting bottom 16 and communicate with a tube 17. In this tube is inserted a housing 18, within which is disposed an exhaust fan, not shown, said fan collecting the loose particles of the grinder or work thrown off during 90 the abrading operation into the housing 15 and forcing or delivering the same into a receptacle 18', shown in Fig. 1 of the drawings. Thus far the construction and operation of the elements are well known, so that a further detailed description thereof seems to be unnecessary.

In each of the housings 15 is rotatably journaled a shaft 19, the same being journaled in bearings 20 upon the sides of the 100

respective housing 15 and extending in parallel relation to the shaft 12 a substantial distance below the same. To the shaft 19 are secured thread-tufts 21 throughout a length which corresponds to the width of the respective housing 15. Each tuft is of a length which is greater than the distance between the shaft 19 and the inner face of the bottom of the housing 15, and also 10 greater than the distance between the shaft 19 and the peripheral portion of the respective abrading wheel or cylinder 14, so that, in the rotation of the shaft 19, the said tufts are adapted to brush the loose particles from the housing bottom throughout the entire width of the latter and also from the abrading wheel in the respective housing. The shafts 19 may be driven in any suitable manner, for instance each of the 20 same may have mounted thereon a pulley 22. Over these pulleys run belts 23, which run also over the main driving shaft 24 of the machine. The diameter of the pulleys 22 may be smaller than that of the main driving shaft, so that the shafts 19 may be rotated at a considerable speed.

The tufts 21 may be secured to the shafts 19 in any suitable manner, for instance a bunch of threads may be folded back upon 30 itself at its middle portion to form a bight. The bight portion of the bunch is then bent around the shaft 19 and the ends of the bunch extended through the bight and drawn taut on the shaft 19. In order to cause the tuft to adhere properly to the shaft 19, so as to rotate therewith, the bight portion of the thread bunch may be treated with shoe-maker's wax or similar material, sufficient to cause adhesion thereof to

the shaft. In the rotation of the shafts 19, 40 the thread-tufts remove the loose particles from the bottom of the housing and also from the abrading wheels, the said loose particles being then delivered into the receptacle 18'. 45

It is obvious that, since the thread-tufts are flexible, they do not injure the hands of the operator.

It is to be noted that, while herein specific tufts have been described and a specific manner of attaching the same to the shafts 19 has been disclosed, any other material may be used and any other suitable way of attaching the tufts to the shaft may be resorted to without departing from the invention. 55

What I claim is:—

1. An abrading machine including a rotary shaft, an abrading wheel thereon, a housing partly enclosing said wheel having its bottom disposed at a substantial distance below said wheel, air current producing means connected with said housing acting constantly on said abrading wheel, a second rotary shaft journaled in said housing below said first-mentioned shaft, and flexible means on said second-mentioned shaft for removing from the inner face of said housing particles of the grinder or work thrown off during the abrading operation. 65

2. An abrading machine according to claim 1, said flexible means serving also to clean said abrading wheel. 70

Signed at New York, in the county of 75 New York and State of New York, this 28th day of December, A. D. 1923.

BENJAMIN W. KLEIN.
